UNITED STATES PATENT OFFICE.

HARRY T. PARKS, OF CUYAHOGA FALLS, OHIO

COMBINED RAIL CHAIR AND JOINT.

1,106,157.

Specification of Letters Patent.

Patented Aug. 4, 1914.

Application filed April 18, 1914. Serial No. 832,859.

To all whom it may concern:

Be it known that I, HARRY T. PARKS, a citizen of the United States of America, residing at Cuyahoga Falls, in the county of Summit and State of Ohio, have invented certain new and useful Improvements in Combined Rail Chairs and Joints, of which the following is a specification, reference being had therein to the accompanying drawing.

This invention relates to a combined rail chair and joint, and has for its object to provide a device of such class, in a manner as hereinafter set forth, for not only supporting the bases of a pair of track rails, but for further connecting the opposing ends of the track rails together without the employing of nuts and bolts, at the same time providing for the necessary contraction and expansion of the track rails, due to climatic conditions.

Further objects of the invention are to provide a combined rail chair and joint, which is simple in its construction and arrangement, strong, durable, efficient and convenient in its use, readily set up and comparatively inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claim hereunto appended.

In the drawings, wherein like reference characters denote corresponding parts throughout the several views:—Figure 1 is a side elevation of a combined rail chair and joint in accordance with this invention, Fig. 2 is a plan, partly in section, Fig. 3 is a cross sectional view, and Fig. 4 is a detail of the removable splice bar.

Referring to the drawings in detail, 5 and 6 denote a pair of track rails, which have the ends thereof opposing, and each of said rails includes a head 7, web 8 and a base 9. The web 8 of each rail is provided with a plurality of openings 10.

The combined rail chair and joint consists of a chair plate 11 having depending therefrom a pair of longitudinally disposed ribs 12 and 13, constituting reinforcements for the plate 11 and which are arranged be-

tween a pair of ties not shown. The chair plate has one longitudinal marginal portion of its upper face provided with a longitudinally disposed and vertically extending flange 14, having the inner face thereof undercut or beveled as at 15. The chair plate 11 has the other longitudinal marginal portion of its upper face provided with a longitudinally disposed vertically extending flange 16. The flanges 14 and 16 are of greater height than the bases 9 of the track rails. The chair plate 11 supports the bases 9 of the track rails.

Formed integral with a portion of the inner face of the flange 16 is a splice bar 17, which opposes one side of the webs 8 of the track rails, engages the upper face of one side of the bases 9 of the track rails and abuts against the heads 7 of the track rails. The fish plate 17 is provided on its inner face with integral lugs 18, which project into the openings 10 of the webs 8.

The reference character 19 denotes a removable splice bar which is opposed against the other sides of the webs 8 of the track rails, and abuts against the heads 7 of the track rails and engages the bases 9 of the track rails. The fish plate 19 has a depending extension 20, seating upon the upper face of the chair plate 11. The outer edge of the extension 20 is beveled as at 21 and furthermore provided with teeth 22.

When the track rails are mounted upon the chair plate 11, the longitudinal edges 23 of the bases 9 are spaced from the inner side 24 of the flange 16 and the inner side 26 of the extension 20.

To prevent the longitudinal shifting of the splice bar 19 with respect to the chair plate 11, a vertically disposed retaining member 27 is extended through the flange 15, beveled edge 21 of the extension 20 and the said member 27 has its lower end bent at an angle as at 28 to arrest upward movement of said member. The member 27 is disposed at an angle, due to the fact that it engages a beveled wall of one of the teeth 22.

What I claim is:—

A combined rail chair and joint comprising a chair plate having the longitudinal marginal portions of the upper face thereof provided with vertically extending longitudinally disposed flanges, one of said flanges having its inner side undercut, a splice bar formed integral with the other of said flanges and capable of abutting against one

side of a pair of track rails, lugs integral with the inner face of said splice bar and capable of projecting into the webs of the track rails, a removable splice bar capable of engaging the other sides of the track rails and provided with an extension seated upon the upper face of said chair plate, said extension having its outer edge beveled and opposing said undercut inner side, said beveled edge of said extension provided with teeth, a vertically extending angularly disposed retaining member projecting through said undercut flange, said beveled edge and

said chair plate and having its lower end bent to engage the lower face of said chair plate to arrest upward movement of said member, and depending longitudinally extending reinforcements integral with the lower face of said chair plate. 15

In testimony whereof I affix my signature in the presence of two witnesses.

HARRY T. PARKS.
